UNITED STATES PATENT OFFICE.

WILLIAM F. STOCKER, OF EUREKA, KANSAS, ASSIGNOR TO WILLIAM H. BYERS, OF SAME PLACE.

ELECTRIC BELL.

SPECIFICATION forming part of Letters Patent No. 377,539, dated February 7, 1888.

Application filed March 7, 1887. Serial No. 229,962. (No model.)

To all whom it may concern:

Be it known that I, WILLIAM F. STOCKER, of Eureka, in the county of Greenwood and State of Kansas, have invented a new and Improved Electric Bell, of which the following is a specification, reference being had to the annexed drawings, forming a part thereof, in which—

Figure 1 is a side elevation of my improved electric bell. Fig. 2 is a vertical section taken on line $x-x$ in Fig. 1. Fig. 3 is a vertical transverse section of the end of the armature-lever, taken on line $y-y$ in Fig. 2. Fig. 4 is a side elevation of the bushing fitting the armature-lever. Fig. 5 is a plan view of a portion of the forward end of the armature-lever, showing the cross-arms; and Fig. 6 is a plan view of the yoke of one of the electro-magnetic armatures.

Similar letters of reference indicate corresponding parts in all the views.

The object of my invention is to construct an electro-magnetic bell in which a long stroke of the bell-hammer may be secured, so as to produce an effective alarm without the employment of spring or weight actuated mechanism.

My invention consists in the combination, with the bell-hammer lever, of one or more electro-magnetic armatures and one or more helices adapted to receive within their coils the electro-magnetic armatures, either the armatures or the helices being carried by the bell-hammer lever.

To the base A, near one end, is secured the U-shaped frame B, provided with a right-angled arm, C, and having a double offset branch, D, near the base thereof, provided with cross-bars $a-b$. Near the opposite end of the frame is secured a standard, F, which supports a bell, G, in suitable position to be operated by the electro-magnetic mechanism.

In the frame B are inserted screws c , forming the pivots of the armature-lever E. One end of the armature-lever E projects forward to a point underneath the bell G, and is provided with a hammer, H. The hammer end of the armature-lever is reduced in thickness, to allow it to spring forward and strike the bell after the movement of the body of the lever is ar-

rested by the limiting-screw d , inserted in the bar a of the arm D. The downward motion of the hammer end of the lever E is limited by a screw, e , inserted in the cross-bar b . The end of the armature-lever opposite that to which the hammer H is applied is provided with a bearing, f , for the bushing g , (shown in detail in Fig. 4,) and the said bushing is held in place in the bearing by a cap, h , secured to the armature-lever by screws i .

In the bushing g is received the rounded central portion of the iron yoke I, and to the yoke, near opposite ends, are secured soft-iron cores J, which project downwardly toward the base A. Upon each of the cores J is secured a bobbin, K, and to the base A, underneath the cores J, is secured an iron plate, j , upon which are placed the helices L, which are axially in line with the cores J. The cores J hang from the armature-lever, and enter a short distance into the bore of the helices L, in position to be acted upon by the helices when energized by an electric current.

To the armature-lever E, at the opposite side of the fulcrum of the said lever, is connected a pair of cores, J', similar to the cores J, already described. The cores J' are attached to an iron yoke, I', and are bored transversely and received on trunnions formed on the ends of a non-magnetic cross-arm, k, formed on or carried by the armature-lever.

To the arm C of the frame B is secured an iron plate, j' , to which are attached two helices, L', which are similar in connection and arrangement to the helices L, already described. The cores J' are provided with bobbins K', and normally enter a short distance into the bore of the helices in position to be acted upon by the magnetism developed in the helices when they are subjected to the action of an electric current.

To the armature-lever E, near its fulcrum, is secured one end of a spiral spring, l, the opposite end of which is connected with a thread wound around the spindle M, passing through the arm D. The spring serves to quicken the retrograde movement of the hammer, so that the strokes of the bell may be repeated in quick succession. The current from any source of electricity, entering the bell by the binding-

post *m*, is conveyed to the helices *L* by the wire *n*, and from the helices *L* by a spiral wire, *o*, to the bobbins *K* on the cores *J*, and the bobbins *K* are connected electrically with the helices *L'* by the spiral wire *p*. The current finally returns to the remaining binding-post, *m'*, by a spiral wire, *q*, the bobbin *K'*, and the wire *r*.

The helices *L* and the bobbins *K* are wound 10 in opposite directions, so as to produce in the helices and in the cores *J* poles of opposite name, to secure the drawing of the cores *J* into the helices *L*. In like manner the helices *L'* and bobbins *K'* are wound in opposite directions, so as to secure the drawing of the cores 15 *J'* into the helices *L'*.

As my improved bell is designed for heavy work—such as railroad-signaling, fire and burglar alarms—it is desirable to place it in the 20 local circuit provided with a strong battery, and operate the local circuit by means of a relay. As the relay and local-circuit connections are of the ordinary kind, it will be unnecessary to enter into a detailed description of 25 them. By providing a long stroke of the electro-magnet or polarized armature I am enabled to secure a powerful blow of the hammer upon the bell.

Should it be desired to produce double 30 strokes on the bell, a forked armature-lever will be employed, carrying two hammers, one upon either side of the bell. If desirable, the ordinary vibratory attachment may be applied to the armature-lever, so as to secure repeated

strokes of the hammer upon the bell during 35 the time contact is formed by the key by which the alarm is sent.

Having thus fully described my invention, I claim as new and desire to secure by Letters Patent—⁴⁰

1. In an electric bell, the combination, with the bell-hammer-operating mechanism, of helices mounted on a plate of magnetic material, electro-magnetic armatures axially in line with the helices and adapted to enter the helices, 45 and the electric connections whereby the polarity of the helices and of the armatures are rendered opposite, substantially as described.

2. In an electric bell, the combination, with the armature-lever *E*, provided with the bearing *f* and cap *h*, of the bushing *g*, the iron yoke *I*, provided with the cylindrical central portion fitted to the bushing *g*, the cores *J*, attached to the yoke *I*, the bobbins *K*, carried by the cores *J*, the helices *L*, adapted to receive the ends of 55 the cores *J*, and the iron plate *j*, substantially as described.

3. In an electric bell, the combination, with the armature-lever *E*, of the base *A*, the frame *B*, provided with the arms *C D*, the limiting-screws *d e*, the retractile spring *l*, the oppositely-arranged helices *L L'*, the electro-magnetic cores *J J'*, the bobbins *K K'*, and the electrical connections, substantially as described.

WILLIAM F. STOCKER.
